WHEELED CARRIER DISPENSER

William H. Frick, Cleveland, Ohio

Application February 2, 1954, Serial No. 28,785

Term of patent 14 years

(Cl. D14—3)

Fig. 1

To all whom it may concern:

Be it known that I, William H. Frick, a citizen of the United States, residing at Cleveland, State of Ohio, have invented a new, original, and ornamental Design for a Wheeled Carrier Dispenser, of which the following is a specification, reference being had to the accompanying drawing, forming a part thereof.

In the drawing:

I claim:

The ornamental design for a wheeled carrier dispenser, as shown.
